Primary Examiner — Vy N Koenig*Assistant Examiner* — Elizabeth Anne Glassberg(74) *Attorney, Agent, or Firm* — George D. Morgan(57) **CLAIM**

The ornamental design for a dog seat, as shown and described.

DESCRIPTION

FIG. 1 is a top perspective view of a dog seat, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 2; and, FIG. 11 is an enlarged detail view of area 11 in FIG. 2.

The long dash-short dash broken lines in FIGS. 1, 2, 9, 10, and 11 show the boundaries of the enlargements shown in FIGS. 9, 10 and 11, and form no part of the claimed design.

1 Claim, 11 Drawing Sheets(56)
